ATTORNEY

UNITED STATES PATENT OFFICE

HAROLD B. ROBBINS, OF WHITE PLAINS, NEW YORK

ATTACHMENT FOR WASHING MACHINES

Application filed May 26, 1930. Serial No. 455,526.

This invention relates to machines for washing fabrics, and more particularly to testing arrangements for determining the conditions to which fabrics are subjected in the process of being washed.

It is common practice in the process of washing clothes or fabrics, to place them in a rotary cylindrical drum provided with perforations through its surface. The cylinder is caused to rotate in a suitable solution of water and soap or other cleansing agent which passes through the perforations and circulates about the clothes or fabrics which are agitated by the rotation of the drum. After the goods have undergone the necessary washing process they are removed from the drum and other goods to be washed are inserted therein. These operations of inserting and removing the goods may continue indefinitely.

It is desirable at suitable intervals to make tests to determine the deteriorating effects, if any, of the washing solution upon the goods. It was formerly customary in making these tests to insert a cloth test piece in the cylinder each time it was filled with goods to be washed, and to remove such test piece with the goods after each washing operation had been performed. This process of testing involved a loss of time in handling, and besides, gave little information as to the effect of the washing solution upon the fabric, due to the short time the test piece was subjected to the chemical action.

Accordingly, it is one of the objects of this invention to provide an arrangement by which the above outlined testing operations may be carried out expeditiously and efficiently.

Another object consists in incorporating such testing arrangement in any well-known type of washing machine in a comparatively simple and inexpensive manner.

The novel features which are considered characteristic of this invention are set forth with particularity in the appended claims. The invention itself, both as to its organization and method of operation, together with other objects and advantages thereof, will be further explained in the following detailed

description having reference to the accompanying drawings, consisting of the following figures:

Figure 1 is a fragmentary view of one end of the cylindrical drum showing the improved arrangement applied thereto.

Fig. 2 is an end view in section of Fig. 1.

Figs. 3 and 4 are elevations of one modification of the improved arrangement, illustrating its closed and opened positions, respectively.

Fig. 5 is an elevation showing another modification of the arrangement.

Fig. 6 is an end view of Figs. 3 and 5, as viewed from the left.

Referring to the drawings, the reference 5 designates a cylindrical drum which forms a receptacle in which the goods to be washed are deposited. This drum is of well-known character and in practice is enclosed in a tubular outer casing (not shown). A washing medium is introduced into this casing, and confined thereby so that it may be circulated through the drum 5 and its contained goods to be washed. The drum is rotatably mounted in a horizontal position on trunnions 6. The drum 5 and its associated elements may be made of any suitable material such as sheet metal, and perforations 7 extend through the drum wall. While only a few of these perforations are shown in the drawings, it will be understood that they are provided substantially throughout the drum to readily permit ingress and egress of the washing solution when the washing machine is in service.

The drum includes a plurality of arcuate members 8 which are formed to provide a series of inwardly extending ribs or baffles 9. The members 9 are disposed longitudinally of the drum, and although shown as being four in number and of substantially U-shape in cross-section, they may be of such number and form as may be desired, their purpose being to lift and agitate the goods to be laundered as the drum rotates. A door 10 is mounted to slide circumferentially of the drum 5, as is more clearly shown in Fig. 2. The door in its open position permits the insertion and withdrawal of goods from the interior of the drum, and in closed position

serves with the drum to provide an enclosure in which the goods are washed. The cover 10 is slidably mounted in a groove 11 provided on the circular surface of the drum, 5 and a shoulder 12 at the end of the groove acts as a stop for the cover to limit its movement in an open position. Latching or fastening means, such as indicated at 13, may serve to securely lock the door when it is in 10 closed position.

An auxiliary receptacle or compartment is provided in one of the ribs or baffles 9, and the wall or end flange 14 of the drum may form one outer wall for such compartment. 15 The lower wall of the compartment is formed by the substantially U-shaped rib 9, and a plate 15 fitted into said rib comprises the inner wall of the compartment. This plate forms a partition in the rib, and it has a 20 flange 16 which is riveted or otherwise suitably secured to the sides and bottom of the rib. The top of the compartment is closed by a perforated arcuate-shaped cover plate 17 which is slidably mounted in parallel 25 grooves 18, 18 provided in opposite sides of the rib section. The plate 17 in the modification shown in Figs. 3 and 4, is provided with a flange 19. This flange is seated on a bracket 20 secured to the wall 14 when the compartment 30 is closed, thereby forming a tight joint to prevent the test fabric from working out during the washing process. The flange acts as a stop to limit the outward travel of the plate 17 when the compartment is fully 35 opened. In the modification shown in Figs. 5 and 6, the plate 17 is provided with a downwardly extending finger 21 which engages the plate 15 to limit the outward movement of the cover plate 17 in the fully opened position 40 of the compartment. In the closed position of the cover plate, shoulder 19 serves to prevent the fabric from working out.

The plate 17 has an angular extension 23 which lies in the rib in a position parallel 45 to the plate 15. In the closed position of the compartment, these plates are secured together by some such means as a stud, which extends through the aperture in the plate 23 and the screw threaded hole in the plate 15, 50 and has wing-like members applied thereto at its outer end in order that it may be easily manipulated. To open the compartment the stud is unscrewed from the opening in the plate 15 and the plate 17 is moved to the left, carrying with it the stud, as shown in 55 Fig. 4.

In the operation of the arrangement, a test cloth of suitable character and dimension is inserted in the compartment and its 60 cover is then closed and locked. The test cloth is retained in the compartment through a comparatively large number of washing operations of different lots of goods. The 65 perforations in the walls of the compartment permit the solution used for washing the

goods contained in the perforated drum to readily circulate through the compartment. The test cloth in such compartment is thus subjected to the same washing conditions as are experienced by a lot of goods which have gone through a considerable number of 70 washing operations. After a desired interval has elapsed, the test piece is removed and examined for whiteness, tensile strength or other tests which it may be desired to make. 75 These tests determine the functioning of the washing machine, the effect of the washing solution, and the quality of the washing.

While there are shown and described herein certain forms of the invention by way of 80 illustration, it will be understood that it is not limited or confined to the precise details of construction herein described and delineated, as modification and variation may be 85 made within the scope of the appended claims without departing from the spirit of the invention.

What is claimed is:

1. A washing machine comprising a rotary mounted receptacle for goods, a plurality of inwardly disposed hollow ribs extending longitudinally of the receptacle, and an auxiliary receptacle for test goods, said auxiliary receptacle having certain of its walls formed from one of said ribs. 90

2. A washing machine comprising a rotary mounted receptacle for goods, a plurality of inwardly disposed hollow ribs extending longitudinally of the receptacle, an auxiliary receptacle for test goods, said auxiliary receptacle having certain of its walls formed from one of said ribs, and a cover plate for the auxiliary receptacle slidably mounted on such rib. 100

3. A machine comprising a rotary mounted receptacle for goods to be washed, a plurality of inwardly disposed hollow ribs extending longitudinally of the receptacle, said receptacle and ribs having perforated walls, an auxiliary receptacle for test goods, said auxiliary receptacle having certain of its walls formed from one of said ribs, and a perforated cover plate for the auxiliary receptacle slidably mounted on the top portion of the walls of such rib. 110

4. A machine comprising a rotary mounted receptacle for goods to be washed, a plurality of ribs substantially U-shaped in cross section extending longitudinally of the receptacle, said receptacle and ribs having perforated walls, an auxiliary receptacle for test goods, said receptacle having certain of its walls formed from one of said ribs, and a perforated cover plate for the auxiliary receptacle slidably mounted on the walls of such rib. 120

5. A machine comprising a rotary mounted receptacle for goods to be washed, end walls for said receptacle, a plurality of ribs substantially U-shaped in cross section extending 125

- between said end walls, said receptacle and ribs having perforated surfaces, a partition in one of said ribs, the walls of said rib and the partition therein together with the segmental portion of one of the end walls of said first mentioned receptacle forming an auxiliary receptacle, and a perforated cover slidably connected with the aforementioned rib.
- 10 6. A machine comprising a rotary mounted receptacle for goods to be washed, end walls for said receptacle, a plurality of ribs substantially U-shaped in cross section extending between said end walls, said receptacle and ribs having perforated surfaces, a partition in one of said ribs, the walls of said rib and the partition therein together with the segmental portion of one of the end walls of said first mentioned receptacle forming an auxiliary receptacle, a perforated cover slidably associated with the aforementioned rib, and means to lock said cover in closed position to retain test fabrics in the auxiliary receptacle.
- 15 20 25 In testimony whereof, I have signed my name to this specification this 23rd day of May, 1930.

HAROLD B. ROBBINS.
